JUNIUS A. MARTIN AND ROBERT L. LEE, OF DURHAM, NORTH CAROLINA; SAID LEE ASSIGNOR, BY MESNE ASSIGNMENTS, OF HIS RIGHT TO CARROLINA AUTOMATIC MACHINERY COMPANY, OF DURHAM, NORTH CAROLINA, A CORPORATION OF NORTH CAROLINA.

CUTTING ATTACHMENT FOR HOSEY-LOOPING MACHINES.

1,374,940.

Specification of Letters Patent. Patented Apr. 19, 1921.

Application filed December 8, 1919. Serial No. 343,262.

To all whom it may concern:

Be it known that we, JUNIUS A. MARTIN and ROBERT L. LEE, citizens of the United States, residing at Durham, in the county 5 of Durham and State of North Carolina, have invented new and useful Improvements in Cutting Attachments for Hosiery-Looping Machines, of which the following is a specification.

10 This invention pertains to an improved thread-cutting attachment for fabric sewing or looping machines. More specifically the structure is designed to be employed in conjunction with machines wherein sections of 15 stockings are sewed together to produce a complete stocking, the operation being such as to leave a uniting chain thread between successively completed stockings, which chain must be cut adjacent each of said 20 stockings. In other words, each chain section between adjacent stockings must be first cut close (or relatively so) to one stocking, and thereafter to the next or adjacent stocking.

25 The present structure is such that the chain thread will be automatically severed between each pair of stockings and a section of such thread bodily removed leaving at each end of the seam produced a short or 30 relatively short end. This double cutting or severance between each pair of stockings does away with the long thread attached to each stocking and does away with the necessity of any after trimming of such long end 35 which occurs in various machines of this type heretofore proposed. The structure is also such that it may be readily attached to any if not all of the so-called looping machines now on the market. Moreover, it contains but few parts, may be economically 40 produced and is not liable to get out of order or become disarranged.

The invention is shown illustrated in the annexed drawings, wherein,—

45 Figure 1 is a top plan view of the cutting attachment shown as applied to a looping machine;

Fig. 2 is an enlarged plan view of the attachment;

50 Fig. 3 an inverted plan view of the same; Fig. 4 a side elevation as seen from the inner side of the structure;

Fig. 5 an elevation as viewed from the

other side, the driving pulley being partly broken away to disclose the polygonal knife; 55

Fig. 6 a front end elevation;

Fig. 7 a rear end elevation;

Fig. 8 a transverse section taken through the driving pulley, the rotary knife and the brush;

Fig. 9 a top plan view of the base plate or member with the brush knife and pulley and the mounting therefor removed; and

Fig. 10 a side elevation of a guard or 60 guide plate.

As shown by dotted lines in Fig. 1, 1 denotes a fixed portion of the circular frame of a looping machine having the usual revolute annulus which is continuously rotated, and provided with a series of equi-distantly 70 spaced points 2 upon which the stockings or socks to be sewn are placed, as is well understood by those skilled in the art.

The present structure may be said to comprise a base member 3 adapted to be attached to the fixed frame 1 by means of a bolt 4. An adjusting screw 4^a passes through the frame and bears upon the upper face of the fixed portion of the looper and by proper manipulation of the bolt 4 and the 80 screw 4^a the forward curved edge 5 of the base 3 may be brought in proper relation to the annulus and the points carried thereby, the proper position being indicated in Fig. 1. The base plate or member 3 is preferably cut away adjacent one side, as at 6, forming a rearwardly extending arm 7, the outer face of which is preferably provided with a horizontally disposed guide-way or recess 8 in which is mounted an 90 adjustable fixed shearing blade 9. Said blade, as will be best seen upon reference to Fig. 5, is slotted adjacent its rear end and is held in its fixed adjusted position by a bolt 10 which passes through the slot and 95 through the upstanding portion of the rearwardly projecting arm 7. Said bolt also serves as the means for securing a thread guide plate 11 in position with reference to the fixed shearing blade and the base plate 100 3. As will be seen upon reference to Fig. 10 the upper edge of the guide plate is downwardly curved toward its outer end or forward end and the under face of its outer end is cut away as at 12, so that when the 105 guide plate is secured in position over the

base 3, a throat or channel is formed between the upper face of the base plate and the outer cut-away end of the guide plate, forming an opening through which the 5 thread chain may be drawn, in the manner hereinafter set forth. The lower wall of the throat is formed upon a radius slightly greater than the radius of the brush, as indicated in Figs. 4 and 9. The fixed 10 shearing blade 9 is, as will be seen upon reference to Fig. 5, curved at its outer end, the curvature being such that the lower portion of the blade extends forward of the remainder of the cutting edge and is in 15 alignment with the curved forward edge 5 of the base. The base 3 is provided with an upstanding lug or bracket 13 to which is pivotally secured by a screw 14, a lever 15, the lever carrying an adjustable stop 20 screw 16, the lower end of which contacts with an abutment 17 formed as an integral portion of the base and limits the downward movement of the lever and the parts mounted thereon. In the outer end of the 25 lever and extending at right angles thereto is secured a fixed shaft 18 upon which is mounted a pulley 19 having an elongated hub 20, which hub is reduced and threaded as at 21. Mounted upon such reduced hub 30 section is a flat disk-like knife or shearing blade 22, and adjacent to said blade and between it and the lever is mounted a circular brush member 23, the body portion 24 whereof bears directly against the adjacent side face of the disk-like rotary knife 22, said elements being held in direct contact with each other and locked for rotation with the hub and pulley by a nut 25 mounted upon the reduced threaded portion 21 of the hub. A spring 26 encircles the shaft 18 and bearing against lock nuts 27 tends to force the pulley, its hub and the parts carried thereby laterally toward the lever 15 and as a consequence when the 40 parts are in their final position, to force the rotary knife and cutter blade 22 into face-wise contact with the fixed shearing blade 9, as will be best understood upon reference to Fig. 6, where it will be seen that 45 the blades overlap. Moreover, as will be seen upon reference to said figure, the tufts of the brush 23 run between the fixed blade 9 and the adjacent parallel guide plate 11. In other words, the fixed blade and the 50 guide plate form a throat or runway through which the brush passes and by which, through the action of the brush, the severed end of the thread is drawn. As will be best seen upon reference to Fig. 5, 55 the rotary knife or shearing blade 22 is polygonal in outline and that it always overlaps the fixed shearing blade 9. When, however, the blade is rotated in the direction of the arrow (Fig. 5) from the position shown in said figure, it will be seen 60 65

that the rotary blade will overlap the fixed blade to a greater extent and this has a direct function in the severance of the thread, as will presently appear. By adjustment of the screw 16 the limit of descent of the 70 gravitating lever 15 and the parts carried thereby may be determined. The adjustment should be such that the shearing blades overlap and that the brush tufts occupy a position within the throat or way formed 75 between the fixed blade and guide plate 11 and touch or nearly touch the curved bottom face of the throat at its forward or intake end and receding therefrom toward the rear of the throatway (see Fig. 5). 80

In operation as the stitched stockings with the connecting chain thread between them are carried along in front of and in proximity to the cutting mechanism above described, the brush while it contacts the 85 seamed portion of the stocking does not draw it inwardly owing to the impalement of the stocking upon the points 2, nor does the brush act to draw that portion of the chain which is immediately adjacent to the 90 stocking against the fixed knife, this by reason of the fact that the chain at such point is held outwardly by its attachment to the impaled stocking. When, however, the stocking is moved on for a slight distance 95 past the brush and shearing mechanism the chain thread which is more or less slack by reason of its not being supported in any way, will be drawn inwardly by the brush and against the forward curved face of the 100 fixed knife and through the rotation of the polygonal shaped rotary blade said rotary blade will make a shearing cut and sever the thread. The severed end is then carried by the brush up between the fixed knife or 105 blade and the guide plate 11, the thread end being carried rearwardly by the brush along the upper curved face of the throat, it being understood that the next stocking to which the thread is then attached is being fed forward. When such stocking approaches the fixed knife the thread will be held against further inward movement by the brush, this owing to the fact that the 110 thread is then held outwardly by its attachment to the oncoming stocking. This has the effect of again carrying the thread at a point adjacent to its attachment to the oncoming stocking across the fixed blade where it is again severed by the continuously rotating cutter or blade. Thus it will be seen that a section of the chain thread is bodily removed between two adjacent stockings and the length of the projecting ends upon each stocking will be found to be substantially the same. The operation will be continued so long as the stockings are fed forward with the intermediate chain thread between them. It is to be noted that there 115 is no intermittent motion of the movable 120 125 130

cutting knife, but on the other hand that it rotates continuously and that there is only one part which is subject to any wear and that is the hub which is mounted upon the 5 shaft. The blades may be readily removed for sharpening when required and by reason of the number of faces which are present upon the rotary blade or cutter it does not have to be sharpened or renewed except 10 at long intervals.

The length of thread left adjacent each stocking may be readily predetermined by the adjustment of the fixed blade or knife 9. If the blade is moved outwardly toward 15 the points upon which the stockings are supported the thread will be cut or severed close to the stocking; if it is adjusted inwardly from the points, the section remaining attached to the stocking will be longer. 20 Thus by a simple adjustment of the fixed blade the length of the attached or remaining thread end at each end of the seam, or to each side of the stocking, may be readily determined and controlled.

25 The term "fixed" as employed in the claims in referring to the blade 9, is to be understood as meaning one which is fixed or stationary when in operation and is not to be construed as precluding adjustment, 30 which, as above noted, is provided and is of importance.

What is claimed is:

1. In a device of the class described, the combination of a fixed blade; a constantly 35 rotating blade; and a brush rotatable with said last named blade, said brush having its axis of rotation located above the path of movement of the thread to be cut, said brush lying adjacent to and working in conjunction 40 with the fixed blade to deflect the thread into operative relation therewith.

2. In combination with a looping machine having a plurality of impaling points arranged in circular series and upon which 45 the fabric to be stitched is placed; a fixed knife standing adjacent the path of travel of said pins; a rotatable knife, the axis whereof lies above the path of movement of the points, said rotatable knife overlapping 50 the fixed knife; and a brush movable with said rotatable knife and adapted to contact the chain stitch between the stitched material and to deflect the same into contact with the fixed knife.

55 3. In a device of the character described, the combination of a supporting element adapted to be secured to a looping machine; a fixed knife carried thereby; a guard plate also secured to the supporting element and 60 forming a throatway with said blade; a shaft arranged above said throatway; a rotatable knife supported by the shaft; and a brush likewise supported by the shaft, said brush at its lower portion extending into 65 the throatway.

4. In a device of the character described, the combination of a supporting element adapted to be secured to a looping machine; a fixed knife carried thereby; a guard plate also secured to the supporting element and 70 forming a throatway with said blade; a shaft arranged above said throatway; a disk-like knife rotatably supported by the shaft; and a brush likewise supported by the shaft, said brush at its lower portion ex- 75 tending into the throatway.

5. In a device of the character described, the combination of a supporting element adapted to be secured to a looping machine; a fixed knife carried thereby; a guard plate 80 also secured to the supporting element and forming a throatway with said blade; a shaft arranged above said throatway; a disk-like knife having a plurality of straight cutting edges mounted for rotation 85 about the shaft; and a brush likewise mounted on the shaft, said brush at its lower portion extending into the throatway.

6. In a device of the character described, the combination of a supporting element 90 adapted to be secured to a looping machine; a fixed knife secured thereto having a vertically disposed upwardly and rearwardly curved edge; a shaft lying above said knife; a rotary disk-like knife polygonal in form 95 supported by the shaft; and a rotary circular brush also supported by said shaft adjacent the knife.

7. In a device of the character described, the combination of a supporting element 100 adapted to be secured to a looping machine; a knife secured thereto with its cutting edge standing in a vertical position; an arm pivoted to said support; means for maintaining the arm in adjusted relation to the blade; 105 a shaft secured in said arm; a disk-like knife mounted for rotation about the shaft; and a flat circular brush also mounted for rotation about the shaft, said brush and disk knife standing at opposite sides of the fixed knife 110 and overlapping the same.

8. In a device of the character specified, the combination of a supporting member; a knife secured thereto with its forward cutting edge standing in a vertical plane, the 115 upper surface of the support to one side of the body of the knife inclining upwardly in a rearwardly direction; a guard plate secured to the supporting member at the opposite side of said surface, said knife, surface 120 and plate forming a throatway; a shaft arranged above said throatway; a disk-like knife mounted for rotation about the shaft with its lower portion overlapping the fixed knife; and a circular brush also mounted 125 for rotation about the shaft, said brush extending into the throatway.

9. In a device of the character described, the combination of a supporting member having an upwardly and rearwardly inclined 130

surface; a knife adjustably secured to the member adjacent one side of said inclined surface, the forward sharpened end of the knife being curved and standing in a vertical plane; a guard plate standing in substantial parallelism to the knife and at the opposite side of said surface; an arm pivoted to the supporting member to the rear of said knife; a shaft mounted in the outer end of the arm; means for regulating the descent of the arm toward the supporting member; a disk-like knife, polygonal in outline supported on the shaft; and a circular brush likewise supported by the shaft, said brush at its lower peripheral portion contacting the inclined surface aforesaid and standing between the fixed knife and the guard plate.

10. In a device of the character described, the combination of a supporting element adapted to be secured to a looping machine; a normally fixed blade adjustable toward and from the fabric supporting points of

the looping machine; a rotary knife coöperating with the fixed blade; and a brush acting to draw the chain thread, between adjacent stockings, into operative relation with the knife and blade. 25

11. In combination with a looping machine having a circular series of fabric sustaining points; a knife having a vertically disposed cutting edge arranged adjacent said points, said knife being adjustable toward and from said points; means for securing the knife in its adjusted position; a rotatable blade coöperating with the knife; 30 and a brush rotatable with said blade, said brush engaging the chain thread between adjacent stitched fabrics and serving to draw the chain into contact with the fixed knife. 35

40 In testimony whereof we affix our signatures.
